ROTARY PUMP AND COMPRESSOR

Percy D. Brewster, Holmdel, N. J., assignor to
Casse Brewster, East Orange, N. J.

Application September 11, 1940, Serial No. 356,249

1 Claim. (Cl. 103—136)

My invention relates to rotary pumps, motors and fluid engines, and particularly to a type of pump consisting of a cylinder in which a rotor revolves, which has a plurality of cavities in its periphery with rollers in them that are adapted to maintain contact between the rotor cavities and the cylinder bore.

In my copending patent application Ser. No. 356,248, filed simultaneously, I described among other things a compound roller for use in this type of pump. The periphery of this roller consists of a plurality of separate concentric rings some of which, at least, are free to revolve in relation to the others. Some of these rings roll on the cylinder bore, others roll on the rotor slots but none of the rings touches both cylinder bore and the rotor. Bearings within the compound roller permit the rings to revolve independently with a minimum of friction.

Throughout the specification and claim the term engine is understood to include pumps, motors and engines driven by fluids. The pump illustrated herein has three independent cavities in the periphery of the rotor but it is to be understood that any number of cavities may be used or the slots may be connected together in the center of the rotor without departing from my invention.

One object of my invention is to provide a roller that rolls in contact with the entire width of the cylinder bore and does not touch the rotor cavity. Another object is to prevent the ends of the roller from touching the inside of the rotor cavities or the cylinder heads. A further object is to reduce the weight of the rollers and rotor. Another object is to provide means at all times for holding the rollers in substantial contact with the cylinder bore. To these and other ends my invention comprises the novel features hereinafter described.

My invention consists in constructing a shroud or header on both ends of the rotor. These headers may be an integral part of the rotor made in one piece or the center portion of the rotor may be cast of a light metal such as an aluminum or magnesium alloy with steel headers at either end integral with the rotor shafts. Slots, equal in number to the cavities in the rotor, are cut in each of the headers spaced equally from one side of each of the said cavities. Shafts, either attached to or mounted to turn in the rollers, are adapted to roll in the slots in the header or to turn in a bearing that either rolls or slides in the said header slots.

The rollers are maintained in substantial con-

tact with the cylinder bore by an extension of the roller shafts through the rotor headers into grooves turned in both cylinder heads concentric with the cylinder bore. The grooves are sufficiently wide so that while the rollers are in actual contact with the cylinder bore, these extension shafts do not touch the sides of the grooves, but if the rollers leave the cylinder bore a substantial distance, this shaft extension comes into contact with the inside of the groove and prevents the rollers dropping into the cavities.

Fig. 1 in the drawings is an end elevation of the pump with cylinder head removed; Fig. 2 is half a top view of the pump and half a section on line AB, Fig. 1; Fig. 3 is an inside view of a cylinder head; Fig. 4 is an enlarged section on line CD, Fig. 1; Fig. 5 is a section through a modified form of roller; Fig. 6 is an end elevation of the roller shown in Fig. 5; Fig. 7 is a section through a modified form of roller; and Fig. 8 is an end elevation of roller shown in Fig. 7.

The pump consists of a cylinder bore 2 in which the rotor 3 revolves with its periphery just clearing the cylinder bore at one point and journaled in the cylinder heads 4 and 5. Three independent cavities 6, 6, 6 in the periphery of the rotor 3 contain the rollers 7, 7, 7. Headers 8, 8, preferably of steel with shafts 9, 9 in one piece, are attached onto either side of the rotor 3 to form the complete rotor. When in clockwise operation, the fluid enters the inlet 10 and passes through port 11 into the pump and is discharged through port 12 and outlet 13. Three slots 14, 14, 14 are cut in each header an equal distance from one side of each of the cavities. The rollers 7 may be cast in one piece but, preferably as illustrated in Figs. 1 and 4, they are made of tubing with headers at both ends to which stub shafts 15, 15 are attached which extend into the slots 14. A bearing 16, usually a ball bearing is mounted on these stub shafts, the outer race of which is adapted to roll on the sides of the slots 14. The slots 14 are preferably sufficiently wide so the outer race of the ball bearing can roll on either face of the slots without touching the other but with the least possible clearance between the bearing and header slots. The stub shaft may pass through the rotor header and extend beyond at 17. A groove 18 is cut in both cylinder heads, slightly wider than shaft 17, so in normal operation it does not touch the sides of the groove, but if the rollers leave the bore of the cylinder, the shaft 17 comes into contact with the groove and keeps the rollers from drop-

ping into the cavities. This groove is not illustrated in Fig. 1 for sake of clarity.

The ends of the rollers 7, 7, 7 are held away from contact with the cylinder heads 4 and 5 and the inside of the rotor headers 8, 8 by the side of the outer race of the bearing 16, Fig. 4, on the roller shaft 15 rolling against the lips 19 on the outside of the roller slot 14. The inner race of this bearing 16 is held against a shoulder on shaft 15 by the snap ring 16a and positions the roller away from the header when the outer race of the bearing is in contact with the lip 19. Any type of thrust bearing may be substituted for this combined radial and thrust bearing. The cylinder heads and the inside of the headers should be in the same plane so a properly positioned roller just clears both of them.

Under certain conditions, the bearings 16 in the rotor header slots may become relatively so large that, when rollers are at the farthest out position in the rotor cavities, the outside of the bearing may touch the bore of recess 20 in the cylinder heads 4 and 5, in which the rotor headers turn, and prevent the rollers for a certain distance from touching the cylinder bore 2. This is avoided by turning a crescent shaped pocket 21 in this recess 20 that is concentric with the cylinder bore and slightly clears the outside of the bearing 16.

A different arrangement of the rollers and the roller shaft is illustrated in Figs. 5 and 6 in which the roller is arranged to turn on shaft 22 by means of bearings 23, 24 within the roller and the shaft is free to roll on the slot 25 in the rotor header 8. The ball bearing 23 is held on its inner race against the shaft shoulder 22a by ring 26 and the outer race is held in position by spring clip 27, while the outer race of the bearing 24 is free to move so this type roller may be also mounted with a thrust bearing in the rotor header slot to keep the roller away from rotor header and cylinder heads.

Figs. 7 and 8 illustrate a roller in which stub shafts 28, 28 are attached to the roller and turn in the cross head 29 which slides in and out in the slot 29a in the rotor header 8. A stub shaft may be driven or pressed into a tight fitting bore

in each end of the roller. Tongues in the top and bottom of the cross head 29 fit into grooves 30, 30 in the rotor header slots to act as a thrust bearing to guide the roller.

5 It is to be understood that bearings of any type, plain, needle, roller, etc., may be readily substituted without departing from my invention. The rollers are so positioned by the bearings in the headers that their periphery does not quite touch the side of the cavity. This exact clearance which is usually a maximum of a few thousandths of an inch is controlled by the size of the pump, the bearings used, the temperatures of the fluid in the pump, etc., and is readily determined by tests, but in no case is a consequential part of the fluid lost by leakage.

While the form of the apparatus herein described constitutes a preferred embodiment of this invention, it is to be understood that the invention is not limited to this precise form of apparatus, and that changes may be made therein without departing from the scope of the invention which is defined in the appended claim.

20 A rotary engine comprising a cylinder having a bore, a cylinder head at each end of the cylinder, fluid inlet and discharge ports for said cylinder, a rotor journaled in at least one of said cylinder heads eccentrically relative to said cylinder bore for rotation therein, said rotor comprising 25 a central portion having a plurality of cavities in its periphery and a header secured to each end of said central portion, radial slots in said headers in alignment with said cavities, the sides of said slots being provided with shoulders 30 spaced from their inner edges, a roller in each of said cavities adapted to contact and roll on said cylinder bore, a shaft extending from each end of each of said rollers into said slots and bearing means on each of said shafts engaging 35 the walls of said slots to prevent engagement of said rollers with the walls of said cavities, said bearing means being secured against axial movement on said shafts and engaging said shoulders on the sides of said slots to prevent the ends of 40 said rollers from contacting said headers.
